METHOD FOR PRODUCING ACETYLACETONE

Eduard Enk and Franz Büttner, Burghausen-Upper Bavaria, Germany, assignors to Wacker-Chemie G. m. b. H., Munich, Germany, a German firm

No Drawing. Application July 19, 1956,
Serial No. 598,757

Claims priority, application Germany August 5, 1955

3 Claims. (Cl. 260—595)

The present invention relates to a method of producing acetylacetone.

It is known to transform isopropenylacetate in the vapor phase at 500° C. into acetylacetone whereby the yield is about 45%. Acetone and ketene, which is decomposed, separating carbon, appear as by-products. The yield diminishes after a short time due to the formation of soot in the reaction chamber which also promotes undesired decomposition of the isopropenylacetate instead of transformation into acetylacetone.

We have found that the separation of carbon can be completely prevented, for all practical purposes, and that the amount of the produced acetylacetone can be considerably increased, if isopropenylacetate in the vapor phase is brought in contact with metallic molybdenum as a catalyst at 300° C. to 600° C. It may be used finely dispersed on an indifferent carrier, for example pumice, whereby the amount of molybdenum may be varied within very wide limits; generally, 2 to 10 percent, by weight, on the carrier are sufficient. The molybdenum may be used as the catalyst in the form of alloys, for example, a molybdenum-iron alloy containing 1.8% to 10% molybdenum. The catalyst may be in the form of balls, turnings, wire coils, and the like.

Example 1

The vapor of 200 grams isopropenylacetate was conducted per hour at 600° C. through a pipe of 600 mm. length and 34 mm. diameter and made of refined steel, the pipe having been filled with 500 ccm. turnings consisting of molybdenum-iron alloy containing 2% by 45

2

weight of molybdenum. The cooled gas exhausting from the pipe separated after three hours 560 grams liquid which was fractionated. Aside from acetic acid and acetone, 390.2 grams acetylacetone was obtained and 5 111 grams isopropenylacetate was regained. This corresponds to a reaction of 65.2% and a yield of 80% of the theoretical yield with respect to acetylacetone. 10 grams acetic acid anhydride, corresponding to 4.1 grams ketene was obtained from the gaseous reaction products. 15 The interior wall of the pipe or oven was entirely free of soot after 21 hours of operation and the yield was unchanged. The acetylacetone was 93% to 95% by weight after the first distillation and contained only one impurity, acetic acid, because it was substantially free of ester and water. The so produced acetylacetone dissolved in 3-N aqueous ammonia, the solution being absolutely clear.

Example 2

The pipe described in Example 1 was filled with 500 20 ccm. pumice granules containing 10%, by weight, finely dispersed molybdenum and having a size of between 5 and 7 mm. The vapor of 600 grams isopropenylacetate was conducted through the pipe during three hours at a temperature of 500° C. 553 grams liquid was obtained 25 from the reaction gases by cooling, which liquid was fractionated. Thereby 299 grams pure acetylacetone and 151 grams isopropenylacetate, which did not react, were produced. This corresponds to a reaction of 50% and a yield of 67% with respect to acetylacetone. The 30 formation continued uninterruptedly for more than 12 hours without any carbon deposits on the catalyst and on the wall of the reaction chamber.

What is claimed is:

1. A method of producing acetylacetone by transforming isopropenylacetate in the vapor phase at a temperature between 300° C. and 600° C. in the presence of metallic molybdenum as a catalyst.
2. A method as defined in claim 1 in which the catalyst consists of a molybdenum-iron alloy containing between 40 1.8% and 10% molybdenum.
3. A method as defined in claim 1 in which the molybdenum is finely dispersed on a carrier made of an indifferent material.
